UNITED STATES PATENT OFFICE.

WILLIAM RANSON, OF PORTAGE, WISCONSIN.

IMPROVED MEDICINE.

Specification forming part of Letters Patent No. **59,070**, dated October 23, 1866.

To all whom it may concern:

Be it known that I, WILLIAM RANSON, of the city of Portage, in the county of Columbia and State of Wisconsin, have invented a new and useful composition of matter, being a Liquid for Curing Fever and Ague and Chill Fever; and I do hereby declare that the following is a full and exact description of the said invention.

The nature of my invention consists in combining the following ingredients: twenty-two grains of quinine, forty-five drops of laudanum, forty-five drops of sweet niter, forty-five drops of elixir of vitriol, and three ounces of water.

Directions for using: One table-spoonful

every three hours on the day the patient does not shake. If he shakes every day, it must not be taken till the fever is off.

Ayer's pills must be taken as follows: Four twelve hours after taking the liquid, then three pills six hours after, and then three more six hours after the last. A sure cure in two days.

What I claim as my invention and desire to secure by Letters Patent, is—

The improved medicine, compounded substantially as herein described.

WILLIAM RANSON.
